[57] ABSTRACT

A cup is selected from a plurality of stacks by first aligning one of a corresponding plurality of arms which are at different heights with a desired dispensing point. A cam is rotated to pivot the arms causing only the aligned arm to effect a dispensing engagement with the dispensing point on the selected stack.

SELECTOR MECHANISM

BACKGROUND OF THE INVENTION

This invention relates to a selector mechanism and more particularly to a mechanism for selecting one of a plurality, i.e., two or more, of dispensing points. The invention is particularly concerned with a selector mechanism which is adapted to be incorporated in a dispensing machine for dispensing a number of different products or articles, for example, separate cups of different beverages.

In known machines for dispensing a number of separate items it is normal for each dispensing unit to be operated by a separate coin mechanism. These individual mechanisms may be quite elaborate and the overall machine is normally large and cumbersome. The mechanism provided by the present invention enables the desired dispensing point to be chosen with the aid of a single selector and the resulting machine is relatively compact.

SUMMARY OF THE INVENTION

In accordance with the present invention there is provided a selector mechanism for a dispensing machine having a plurality of dispensing points, which mechanism comprises a moveable selector adapted to be moveably located in a plurality of separate identifiable positions corresponding to the number of dispensing points, the said selector being attached to a rotatable member having a plurality of operating members rigidly attached thereto, the number of operating members also corresponding to the number of dispensing points and each operating member being associated with a single dispensing point but being in operable relationship therewith only when the selector is located in the corresponding identifiable position and means for pivotably moving the rotatable member to actuate the operating members.

The mechanism of the present invention is particularly suitable for use with a dispensing machine of the type which provides cups containing different powder mixes for subsequent topping up with, for example, hot water to make up different beverages such as tea or coffee. The invention will be more particularly described with reference to such a machine and a mechanism suitable for use in this preferred embodiment is illustrated in the drawing accompanying the Provisional Specification which is a perspective view of a preferred mechanism for operating three dispensing points. The dispensing points illustrated in the drawing are actuating arms A, B and C attached to conventional dispensing rings for dispensing single cups from a stack of cups placed within the ring. The dispensing means themselves are conventional and form no part of the present invention.

DESCRIPTION OF PREFERRED EMBODIMENT

The preferred selector mechanism illustrated in the drawing comprises a moveable selector which comprises a lever having a knob at one end and being pivotally attached at its inner end to a cam follower 2. The lever is adapted to be moved by the knob into separate positions within a gate 3, each position corresponding to the operating position of the associated dispensing point. The cam follower 2 is rigidly attached at a convenient point to a rotatable rod 4 which is supported by 65 bearings 5. The rod 4 has rigidly attached to it arms 6,

7 and 8, to total number of arms corresponding to the number of dispensing points. The selector lever is attached to the cam follower in such a manner as to allow the cam follower to pivot in the vertical direction but to constrain it in the horizontal direction so that when the selector lever is moved within the gate it also moves the rod 4 via the cam follower 2 and consequently the arms 6, 7 and 8. This positioning of the selector lever aligns striker plates 9 attached to the end of the arms 10 with the appropriate dispensing point. In the position illustrated in the drawing arm 6 is lined up with dispensing point A, the selector being in the far left hand position of the gate 3.

To operate the dispensing point chosen it merely remains to raise the front edge of the cam follower plate a suitable amount. In the embodiment illustrated in the drawing a cam is used affixed via a shaft to a knob 10. By twisting the knob, the cam is rotated to raise the plate 2. This action moves the arms 6, 7 and 8 forward but since the striker plate on arm 6 is the only one in line with its associated dispensing point, dispensing point A is the only one to be operated. If the selector lever is moved to the mid position in the gate then this will operate only dispensing point B, and so on for dispensing point C.

The knob 10 is released for turning preferably by means of a coin mechanism which may be either mechanically or electrically operated. Such coin mechanisms are conventional.

In the preferred embodiment illustrated in the drawing the actual selector means is a knob attached to a selector lever but it is to be understood that other selector means, such as for example a knob on a dial with appropriate linkages to the actuating rod 4, may be used. Also, the actual dispensing points may be other than dispensing rings for cups. For example, mechanically operated drawers or slots for packages of sweets or cigarettes.

What we claim is:

1. A selector mechanism for a dispensing machine having a plurality of dispensing points comprising a moveable selector adapted to be moveably located in a plurality of separate identifiable positions corresponding to the number of dispensing points, said selector being attached to a rotatable member having a plurality of operating members rigidly attached thereto, the number of operating members also corresponding to the number of dispensing points and each operating member being associated with a single dispensing point but being in operable relationship therewith only when the selector is located in the corresponding identifiable position and means for pivotably moving the rotatable member to actuate the operating members.
2. A mechanism according to claim 1, in which the moveable selector comprises a lever having a knob at one end and being pivotally attached at its inner end to a cam follower.
3. A mechanism according to claim 2, in which said lever is adapted to be moved by the knob into separate operating positions within a gate.
4. A dispensing mechanism according to claim 3 in which each dispensing point contains a dispensing ring for dispensing single cups from a stack of cups placed within the ring.
